HEATING DEVICE

Filed Sept. 11, 1931

Lutty Hawkins

Geo. P. Kimmel
Attorney

UNITED STATES PATENT OFFICE

LUTTY HAWKINS, OF MOUNT VERNON, ILLINOIS

HEATING DEVICE

Application filed September 11, 1931. Serial No. 562,376.

This invention relates to a heating device adapted for use in connection with chick brooders and has for its primary object to provide a simple and inexpensive structure whereby heat may be applied directly to the backs of chicks in order that chicks in a brooder may be warmed in substantially the same manner as they would be by a hen.

With the foregoing and other objects in view, the invention consists essentially of such parts and combination of parts as set forth in the appended claim.

In the accompanying drawing in which like numerals refer to like parts throughout the several views:

Figure 1 is a vertical section through a heating device in accordance with this invention.

Figure 2 is a bottom plan of the device partly broken away.

Figure 3 is an elevation of the device.

Referring to the drawing in detail, the numeral 1 indicates a supporting frame, preferably of rectangular construction. Seated on the frame 1 is a supporting frame 2 which is recessed in its lower and inner peripheral faces as indicated at 3 to receive a heat insulating plate 4 of asbestos or the like. The upper and inner peripheral faces 30 of the supporting frame 2 are recessed as indicated at 5 to receive a cover plate 6 which is held in position by means of a retaining frame 7 seated thereon and on the supporting frame 2. The frames 7 and 2 are secured to the frame 1 by means of a plurality of holdfast devices 8. The lower face of the supporting frame 1 is recessed as indicated at 9 to receive therein marginal portions of a flexible bottom 10 preferably formed of

rubber. The bottom 10 is secured in position with respect to the frame 1 by means of a retaining frame 11 seated on the portion of the bottom 10 disposed within the recesses 9. The retaining frame 11 is maintained in position with respect to the frame 1 by means of a plurality of holdfast devices 12.

Carried by the heat insulating plate 4 and projecting therefrom into the space 13 between the plate 4 and bottom 10 are a plurality of insulator pins 14 which support a

resistance coil 15. One end of the resistance coil 15 is connected with a conductor 16 extending around an insulator pin 17 and connected with one terminal 18 of a thermostat 19. The opposite end of the resistance coil 15 is connected to a lead in wire 19 extending around an insulator pin 20. The other terminal 21 of the thermostat 19 is connected with a similar lead in wire 22. The thermostat 19 includes a bi-metallic element 23 having one end secured to the terminal 18 and having its other end adjacent but spaced from the terminal 21. Contact between the element 23 and terminal 21 is made by means of a metal stem 24 threaded through the terminal 21. The stem 24 projects upwardly through the plate 4 and cover 6 and is insulated from the latter by means of an insulating sleeve 25. Secured to the outer end of the stem 24 is an insulating button 26 by means of which the stem may be rotated to adjust the inner end thereof with respect to the element 23.

In assembling the device, the insulator pins and thermostat are secured to the plate 4, after which the plate 4, frame 2, cover 6 and retaining frame 7 are assembled and connected to the supporting frame 1 by means of the holdfast devices 8. The connections between the resistance coil 15 and lead in wires 19 and 22 are then made, after which the bottom 10 is secured in position by means of the retaining frame 11 and holdfast devices 12. In the use of the device, the space 13 is heated by the resistance coil 15, and the heat transmitted to the bottom 10 which is positioned within a brooder in a manner to have direct contact with the backs of the chicks within the brooder. Owing to the flexibility of the bottom 10 the latter will substantially conform in contour with the backs of the chicks whereby the latter will be warmed in substantially the same manner as they would be if brooded with a hen.

While the embodiment of the invention herein illustrated and described represents a preferred example of the heating device, it is to be understood that changes in the details of construction may be made which fall within the scope of the appended claim.

I claim:—

- A heating device comprising, a pair of superposed horizontal frames, the upper of said frames having its lower and inner peripheral faces formed with a recess, a heat insulating plate having marginal portions disposed within said recess, said upper frame having its upper and inner peripheral faces formed with a recess, a cover having marginal portions disposed within the recess in the upper and inner peripheral faces of the upper frame, a retaining frame secured to said upper frame for maintaining said cover in position, a flexible bottom member secured to the lower face of the lower of said frames, and electrical heating means disposed between said plate and bottom member.
